UNITED STATES PATENT OFFICE

171,022

EXHAUST PIPE JETTISON

Norman D. Armstrong, Burbank, and Clifford L. Anderson, Los Angeles, Calif.

Application February 12, 1953, Serial No. 23,578

Term of patent 3½ years

(Cl. D14—6)

To all whom it may concern:

Be it known that we, Norman D. Armstrong and Clifford L. Anderson, citizens of the United States, residing in the cities of Burbank and Los Angeles, respectively, county of Los Angeles and State of California, have invented a new, original, and ornamental Design for an Exhaust Pipe Jettison, of which the following is a specification, reference being had to the accompanying drawings, forming part thereof.

Fig. 1 is a top perspective view of an exhaust pipe jettison showing our new design.

Fig. 2 is a bottom perspective view thereof.

Fig. 3 is a front view.

We claim:

The ornamental design for an exhaust pipe jettison, substantially as shown.

NORMAN D. ARMSTRONG.
CLIFFORD L. ANDERSON.
